(57) **CLAIM**

The ornamental design for a container for wet and dry wipes, as shown and described.

DESCRIPTION

FIG. 1 is a perspective view of a container for wet and dry wipes, shown from front, above and right end;

FIG. 2 is a perspective view of the container of FIG. 1, shown in an alternate condition;

FIG. 3 is a front view of the container of FIG. 1;

FIG. 4 is a back view of the container of FIG. 1;

FIG. 5 is a right side view of the container of FIG. 1;

FIG. 6 is a left side view of the container of FIG. 1;

FIG. 7 is a top plan view of the container of FIG. 1; and,

FIG. 8 is a bottom plan view of the container of FIG. 1.

The broken lines shown in FIG. 2 form no part of the claimed design.
